PATENTED JUN 28 1870

4191

United States Patent Office.

ELHANAN OMENSETTER, OF PHILADELPHIA, PENNSYLVANIA, ASSIGNOR
TO SAMUEL MACFERRAN, OF SAME PLACE.

Design No. 4,191, dated June 28, 1870.

DESIGN FOR IRON RAILING.

The Schedule referred to in these Letters Patent and making part of the same.

I, ELHANAN OMENSETTER, of the city of Philadelphia and State of Pennsylvania, have invented and produced a new and original Design for Iron Railing, of which the following is a specification.

The nature of my design is fully represented in the accompanying photographic illustration, to which reference is made.

The photograph represents a side elevation of a panel of a fence, composed of longitudinal rails A A' and open pales B.

The perpendicular rods C C of the pales B connect at the lower ends with the rail A, and the corner leaves a a, which have between them a pendent leaf, b.

The lower ends of said rods terminate in double scrolls d d, having conical projections e e.

The upper ends of said rods are brought together, forming a gothic arch, f, which is ornamented in front by the leaves g g, which face the rail A'.

On the top of the arch f is a crown-leaf, h. Inside of the arch there are double scrolls d' d', similar to the scrolls d d.

The middle portions of the rods C C have an ornament, D, having circular openings j, partly covered by the central ornament E.

The rails A A' have ornamental bands, k, at their ends, and between the pales B.

I claim as my invention—

The design for iron railing, as shown.

In testimony that the above is my invention, I have hereunto set my hand and affixed my seal this 23d day of April, 1870.

ELHANAN OMENSETTER. [L. S.]
